UNITED STATES PATENT OFFICE.

ANGELA C. KAUFMAN, OF LOS ANGELES, CALIFORNIA.

DESIGN FOR A STATUETTE.

Application filed August 2, 1923. Serial No. 6,925. Term of patent 7 years.

o all whom it may concern:

Be it known that I, ANGELA C. KAUFMAN, citizen of the United States, residing at Los Angeles, in the county of Los Angeles and State of California, have invented a new, original, and ornamental Design for Statuettes, of which the following is a specification, reference being had to the accompanying drawing, forming part thereof.

The figure is a front view of a statuette, showing my new design.

I claim:

The ornamental design for a statuette, as shown.

ANGELA C. KAUFMAN.
